JOHN FLEMING AND JOHN HAMILTON, OF PITTSBURG, PENNSYLVANIA.

Design No. 3,760, dated November 23, 1869.

DESIGN FOR A PITCHER.

The Schedule referred to in these Letters Patent and making part of the same.

We, JOHN FLEMING and JOHN HAMILTON, both of Pittsburgh, in the county of Allegheny, and State of Pennsylvania, have invented and produced a new and original Design for Pitchers, of which the following is a specification.

The nature of our design is fully represented in the accompanying photographic illustration, to which reference is made.

We claim, as our invention, the design for a pitcher, as shown.

JOHN FLEMING.
JOHN HAMILTON.
